UNITED STATES PATENT OFFICE.

MAX KRAUT, OF LOS ANGELES, CALIFORNIA.

ORE-SEPARATOR.

1,322,909.

Specification of Letters Patent. Patented Nov. 25, 1919.

Application filed May 26, 1917. Serial No. 171,085.

To all whom it may concern:

Be it known that I, MAX KRAUT, a citizen of the United States, residing in the city and county of Los Angeles, State of California, have invented an Improvement in Ore-Separators, of which the following is a specification.

My present invention relates to ore separating machines working by the well-known 10 flotation method of operation.

It relates particularly to improvements upon a machine which is patented to me and F. B. Kollberg in Letters Patent No. 1,174,737, issued March 7, 1916. That 15 machine shows the cylindrical revoluble member which I employ and other features of my present invention, which will be learned from the description contained in the Letters Patent referred to; but a characteristic feature of it and one which I have 20 found in practice to be objectionable for several reasons is a froth-collecting chamber disposed along the side of the machine for its entire length.

In my present machine, however, I dispense with this chamber, and substitute for it a froth-collecting device mounted upon the top of a casing, preferably cylindrical, containing a revoluble agitating member, 25 substantially like the one in the patent referred to. There are details of this froth-collecting device which I will describe later; but it will be seen that by the disposition of it which I have made, I reduce the floor 30 space necessary for each machine by nearly one-half without increasing the headroom required more than a few inches. In the design of a practical machine which I have here disclosed, it is only about six inches.

While that is a great advantage, a still greater advantage is that by the position of the froth-collecting device, assisted to a certain extent by its construction, I increase the efficiency of the machine by about 50%, 45 as far as I can tell from the tests which I have been able to make up to the present time. This increase of efficiency is not attended by any increased consumption of power; although that would not be of much 50 importance if the increased output could be obtained from the smaller number of machines needed, but it nevertheless affects the total of operating costs favorably. The disposition of the froth-collecting device in 55 the way referred to insures that no part of

the metal will be returned to the pulp after it has been separated therefrom, and at no part of the cycle of operation will the air-bubbles which carry up the particles of metal have their direction of travel reversed. 60 This is a very great advantage, inasmuch as when an air-bubble is forced downward through the pulp even for a short distance, the particle of metal attached thereto is liable to be brushed off and to pass away 65 with the tailings.

There are other details which I will describe and which I aim to cover by the claims, it being obvious that the essential features of the invention may be adopted in 70 whole, or in part, as may be desired.

The accompanying drawings show an embodiment of my invention. Therein:

Figure 1 is a longitudinal vertical section upon the line 1—1 of Fig. 2; 75

Fig. 2 is a transverse vertical section upon the line 2—2 of Fig. 1; and

Fig. 3 is an end elevation looking to the right in Fig. 1.

Fig. 4 is a detail.

In all of the drawings, A is a case, preferably cylindrical, which may be constructed in any desired manner customary in the art, although I have here shown it as made of iron or steel, bolted and riveted in the usual 85 way, like the construction of steam boilers, or of other mining machinery. The case is formed on the top with a longitudinal extension consisting of the side walls A¹—A¹, and the flanges A²—A², which may be 90 hinged as shown, or may be fixed in position. This upward extension, located at the top of the periphery, constitutes the froth-collecting device, which I have called a collector, or froth-chamber, these terms being 95 common in the art. By hinging the flanges A²—A², I have been able to raise one side or the other of the chamber to a greater height, and thus to compel the froth to be discharged upon one side only, if that be desired. Ordinarily, it will be found best to 100 secure these flanges in place and to allow the froth as it accumulates to flow over both of them into the launders. At the bottom of the machine at one end is a feed pipe B, through which is fed into it the pulp, consisting of finely ground ore with water sufficient to form a freely moving fluid mass, and with the addition of a certain percentage of oil, running from about two-tenths of a 110

pound to two pounds per ton, depending upon conditions with which mining operators are familiar, and which need not be stated.

5   Mounted upon a shaft H, of sufficient diameter to prevent flexure, are spiders D D, which carry a cylindrical covering of wooden blocks D¹ having mounted upon their outer periphery ruffles d, and which are 10 perforated at desired intervals with holes d¹. At each end of the revoluble member is a conical air-duct E by which the air has access to its interior; it will be observed that the ducts are of substantial size. The shaft is 15 supported in bearings H¹ H¹, and is shown as driven by a pulley H²; but obviously any other means, such as an electric motor, may be used to drive the machine.

20   The construction of the revoluble member is sufficiently indicated in the prior patent to me and Kollberg, to which I have already made reference, and will not be herein further described.

25   At each end of the machine there are headers I—I¹, which constitute the main support thereof, and at the upper end of the machine opposite the feed pipe B is a tailing pipe G. A tank or receptacle G¹ is provided at that end of the machine which 30 communicates with the froth-collecting chamber; within the tank is a partition G², the effect of which is to keep the froth from flowing out into the tailings pipe, while permitting the tailings to pass thereinto freely.

35   In the froth-collecting device are disposed longitudinal partitions C and transverse partitions C¹ C¹. The longitudinal partitions extend throughout the whole length of the froth-collecting device, and they are disposed so as to incline, at their upper sides, toward the periphery of the revoluble member where it enters between the side walls A¹ A¹. The partitions are shown as substantially parallel; but it is of importance that 40 these should be to a certain extent adjustable so as to produce the best effect with the particular mixture upon which the machine is working. In general the adjustment of the partitions should leave them tilting toward 45 the entering side of the chamber, and I have found no conditions under which it is desirable that they should pass the vertical; but I do not mean to exclude such an adjustment, if it shall be found best in the operation 50 of the machine on any particular pulp; and this disposition of them permits them to catch the spray carrying the pulp; the air-bubbles then find their way upward into the froth-collecting tank or chamber while the 55 tailings accumulate and may fall back into the cylinder to a certain extent, but they are gradually worked along in the bottom of the collector as the machine operates, until they 60 finally flow into the tank G¹, and leave it 65 at the tailings pipe G.

Fig. 4 shows in detail upon a somewhat larger scale a way of adjusting the partitions C. These are shown mounted upon pins at c and connected together at one end by a lever C², connected to a hand-lever C³, mounted in a stand C⁴. When it is desired to adjust the partitions simultaneously, the lever C³ may be moved and this will be effected; any common form of friction device, not shown, may be employed with the 70 lever C³ to hold it in position.

The partitions C are provided at the top with handles c¹ and each of the partitions is attached to the lever C² by bolt and wing-nut c², working in a slot c³ in the lever. By 80 this arrangement the partitions C are made individually adjustable, which is sometimes desirable.

It will be observed that the air ducts E E allow a complete communication with the 85 atmosphere and this dispenses entirely with the pipes formerly employed to bring air into the pulp in what was a separate spraying chamber, as shown in our former patent. The air is introduced not so much by 90 centrifugal force, although there may be a slight amount of that, as by the suction produced by the discharge of the pulp from between the periphery of the revoluble member and the wall of the drum A; as 95 the liquid pulp passes along, there is a considerable suction at all points, which is greatest near the top of the body of liquid in the drum just where the spray enters between the side walls A¹ A¹ of the froth-collector. 100

The operation of my improved machine will be apparent to those familiar with the flotation process, as now well known in this art. The pulp is fed into the pipe B at 105 such a rate as the machine can take care of, the revoluble member being rotated at about 200 R. P. M. in the direction indicated by the arrow in Fig. 2. The pulp passes around to the right, until it reaches 110 the froth-collector chamber, and then passes up between the partitions C C, gradually working along to the tank G¹, passing under the wall G², the froth flowing over the flanges A² A² into the launders as it accumulates, and being prevented by the partition G² from passing into the tailings pipe to any substantial extent; the tailings, however, pass into the pipe and are carried away in the usual manner. 115

It will be seen that the machine embraces a number of advantages over any with which I am acquainted. The froth-collecting device may discharge at either side, or both sides at will. The froth has substantially no downward motion, and does not move at any time against the stream of pulp; after the bubbles are formed until the froth reaches the collector, it passes upward with the motion of the fluid; the dis- 120 125 130

position of the longitudinal divisions of the froth-collector greatly assists the formation of the froth and gives it ample opportunity to rise to the top of the stream of pulp; the longitudinal divisions act as efficient skimmers; the ducts E provide free communication between the atmosphere and the inside of the revolving drum, dispensing altogether with the spraying chamber and air-pipes of former constructions; the power required is certainly no greater, and is probably less than any former construction; and the efficiency of the machine is greatly increased, while the floor space demanded is substantially diminished.

I claim as my invention:

1. In an ore-separator working by the flotation process, a horizontal drum, a horizontal revolute member therein, the drum and revolute members being so related as to convert the pulp fed to the drum into spray and deliver the spray out of the drum, an open-bottomed froth-separating chamber superposed on the drum in position to receive the spray directly as it is projected from the revolute member and adapted to retain a froth-separating body of pulp.
2. In an ore-separator operating by the flotation process, a horizontal drum, a horizontal revolute member therein, the drum and revolute member being so related as to convert the pulp fed to the drum into spray and deliver the spray out of the drum, means for rotating the member, a connection from the atmosphere to the inside of the member, means for feeding a mixture of ore, water and oil to the bottom of the drum, and an open-bottomed froth-separating chamber superposed on the drum.
3. In an ore-separator operating by the flotation process, a horizontal drum, a horizontal revolute member therein the periphery of which is closely adjacent to the drum and is provided with perforations, a connection from the atmosphere to the inside of the revolute member, the drum and member being so related as to convert the pulp fed to the drum into spray and deliver the spray out of the drum, means for supplying pulp to the drum, an open-bottomed froth-separating chamber superposed on the drum and arranged to receive the spray projected therefrom, and partitions in the froth-separating chamber in the path of the spray.
4. In an ore-separator operating by the flotation process, a substantially cylindrical horizontal chamber, a revolute member therein adapted to convert the pulp into spray and deliver the spray out of the chamber, there being perforations in the periphery of the revolute member and a connection from the atmosphere to the inside thereof, means for rotating the revolute member, means for supplying pulp, a froth-separator having open connection with the chamber and arranged to receive the spray directly as it is projected out of the chamber, the separator containing partitions, and means for adjusting the partitions to different angles of incidence with the spray entering the froth separator.
5. In apparatus for separating ore by the flotation process, means for feeding pulp, means for spraying the pulp and projecting the spray, a froth-separator arranged to receive the spray as projected and provided with partitions, and means for adjusting the partitions to different angles of incidence with the spray entering the separator.
6. In apparatus for separating ore by the flotation process, means for feeding pulp, means for spraying the pulp and projecting the spray, a froth-separator arranged to receive the spray as projected and provided with partitions, and means for adjusting the partitions individually to different angles of incidence with the spray entering the froth-separator.
7. In apparatus for separating ore by the flotation process, means for feeding pulp, means for spraying the pulp and projecting the spray, a froth-separator arranged to receive the spray as projected and provided with partitions, and means for adjusting the partitions to different angles of incidence with the spray entering the separator, the partitions arranged at an angle greater than a right-angle with the spray entering the froth-separator.
8. In apparatus for separating ore by the flotation process, means for feeding pulp, means for spraying the pulp and projecting the spray, a froth-separator arranged to receive the spray as projected and provided with longitudinal partitions, and means for adjusting the partitions to different angles of incidence with the spray entering the separator.

In testimony whereof I have signed my name to this specification this 19th day of May, 1917.

MAX KRAUT.
